(57) **CLAIM**

I claim the ornamental design for an air dam cover for vehicle, substantially as shown and described.

DESCRIPTION

FIG. 1 is a top perspective view of the air dam cover for vehicle.

FIG. 2 is a top plan view thereof.

FIG. 3 is a bottom plan view thereof.

FIG. 4 is an elevational view as taken from the right side of FIG. 2.

FIG. 5 is an elevational view as taken from the left side of FIG. 2.

FIG. 6 is a rear elevational view as taken from the rear of FIG. 1; and,

FIG. 7 is a front elevational view as taken from the front of FIG. 1.
